POLYNITROPHENOLS

Carl E. Moore, Chicago, Ill.

No Drawing. Application September 9, 1954,
Serial No. 455,075

7 Claims. (Cl. 23—230)

This invention relates to reagents in the form of trinitrophenols.

The separation or qualitative analysis for barium, strontium and calcium is particularly difficult, and the primary object of the present invention is to enable this to be accomplished with relative ease by means of a 3-methyl-5-n-propyl-trinitrophenol reagent that will precipitate barium in relatively large quantities while having but slight precipitating action on strontium and calcium in a mixture containing the three. A further object of the present invention in this connection is to enable analysis to be made for cerium, lanthanum, beryllium, cesium, aluminum, lead, copper, chromium and iron by means of a 3-methyl-5-n-propyltrinitrophenol reagent that exhibits contrasting precipitates for these metals.

A further object of the present invention is to enable lanthanum or lead to be determined in a mixture containing lanthanum or lead or both in the presence of one or more of the following: Na^+ , Li^+ , Cu^{++} , Ca^{++} , Mg^{++} , Ni^{++} , Al^{+++} , Hg^{++} , Co^{++} , Zn^{++} , Mn^{++} , Cr^{+++} , Cd^{++} , Fe^{++} , Cs^+ , NH_4^+ by means of a reagent in the form of 3-isopropyl-2,4,6-trinitrophenol.

Other and further objects of the present invention will be apparent from the following description and claims which, by way of illustration, show preferred embodiments of the invention and the principles thereof and what I now consider to be the best modes in which I have contemplated applying those principles. Other and further objects of the invention embodying the same or equivalent principles may be used and changes may be made as desired by those skilled in the art without departing from the present invention and the purview of the appended claims.

I Synthesis of 3-methyl-5-n-propyltrinitrophenol

In each of three 500 cc. flasks place 210 cc. (1.6 mole) of ethyl acetoacetate. Chill in an ice-salt bath and add 0.77 mole butyraldehyde to each flask. Cool to 0° C. and add, with shaking, to each flask a mixture consisting of 3 cc. piperidine and 5 cc. ethanol. Maintain each flask in an ice-salt bath for six hours, combine the contents of the three flasks and refrigerate for three days while adding an additional mixture of 3 cc. piperidine and 5 cc. ethanol each day. After completion of the foregoing, allow the system to stand one day at room temperature to obtain the following ester product:

The yield, a crude bis-ester (viscous oil), is melted on a steam bath and poured into a mixture of 600 cc. acetic acid and 40 cc. concentrated sulfuric acid. To this is added about 10 g. of boiling chips. Reflux for one hour. Pour the mixture (with stirring) into 2 litres of ice-water, establish separate layers by adding ether and decant to obtain the organic layer. The organic layer thus separated is stirred with 1200 cc. water and neutralized at the same

2

time by slow addition of sodium carbonate. The mixture is again decanted, and the following cyclic product (4-carbethoxy-3-methyl-5-n-propyl-2-cyclohexene-1-one) is obtained in an ether solution:

5

10

The aforesaid ether solution is heated gently under reduced pressure until all the ether is evaporated, and to the carbethoxy residue is added 1020 cc. water, 180 cc. 95% ethanol, and 130 g. NaOH. The resultant solution is then heated on a steam bath with stirring until the ester is dissolved. Reflux for 15 minutes, and then carefully acidify with a solution of 100 cc. concentrated sulfuric acid in 200 cc. water while cooling the flask with a stream of water. The acid is added at a rate compatible with the evolution of CO_2 . The acidified mixture thus obtained is then refluxed for 15 minutes, cooled to room temperature and the layers separated. The crude product thus obtained is diluted with ether and washed with two 100 cc. portions of 5% NaOH solution followed by 100 cc. of 5% aqueous acetic acid. The ether solution is dried over anhydrous sodium sulfate and distilled under reduced pressure to obtain the following product (3-methyl-5-n-propyl-2-cyclohexene-1-one) having a boiling point of 110–113° C. at 9 mm.:

35

25

5 g. of the 3-methyl-5-n-propyl-2-cyclohexene-1-one product is mixed with 75 cc. trimethyl benzene (mesitylene-Eastman Kodak crude redistilled) and 1.5 g. of a standard 5% palladium-carbon catalyst. The mixture is subjected to a vigorous reflux at 160° C. for 2 hours and then cooled to 50° C. The catalyst, which cannot be reused, is removed by filtration, and washed with four 5 cc. portions of hot ethyl acetate. The product in solution is subjected to liquid-liquid extraction with three 40 cc. portions of 10% NaOH solution. The combined extracts are washed with 40 cc. pentane, then diluted with 100 cc. water, and 5 cc. of concentrated hydrochloric acid are added thereto. The acidified solution is chilled in an ice bath, further acidified with dilute hydrochloric acid and re-chilled for several hours. The product is removed by ether extraction, and the ether is evaporated under reduced pressure to obtain the following:

60

To nitrate the 3-methyl-5-n-propyl product, 3 to 4 g. thereof are acidified with 30 cc. of concentrated sulfuric acid, stirred and cooled. 30 cc. of concentrated nitric acid are added dropwise while cooling and stirring. The resultant mixture is poured over approximately 50 cc. of ice. When the ice melts, the product in the form of red-black amorphous crystals is filtered off. These are redissolved in 25 cc. of hot ethyl alcohol. Then 25 cc. of a 5% NaOH solution are added followed by the addition of 50 cc. of a saturated KCl water solution. The

following product in the form of bright yellow crystals is cooled and filtered off:

To purify, the above described potassium salt is recrystallized from water. The phenol is regenerated by adding concentrated hydrochloric acid to a saturated water solution of the aforesaid potassium salt. The resulting solution is cooled and the free phenol shown below having a melting point of 74-75° C. is filtered off:

II Preparation of 3-methyl-5-n-propyltrinitrophenol reagent

Add one-half g. of 3-methyl-5-n-propyl-trinitrophenol prepared as above to 15-20 cc. water to produce approximately a 3% solution, and add 1 N. NaOH thereto until the pH is adjusted to 6.5. The reagent thus prepared will produce the following precipitates from an aqueous solution:

	Metal	Relative Amount of Precipitate
1	{Ba ⁺⁺ , Ce ⁺⁺⁺ , La ⁺⁺ , Cs ⁺ , Pb ⁺⁺ , Sr ⁺⁺ , Ca ⁺⁺ , Al ⁺⁺⁺ , Cu ⁺	Large.
2		Slight.
3		Minute.

Use of the foregoing reagent produces an oil in the presence of the following metals: Be⁺⁺, Cr⁺⁺, and Fe⁺⁺⁺.

III Synthesis of 2,4,6 trinitro-3-isopropylphenol

To 5 g. of the 3-isopropylphenol add 60 cc. concentrated H₂SO₄. Warm gently until the temperature is 60° C. Cool to 0°-5° C., and add dropwise 20 cc. concentrated HNO₃ keeping the temperature below 15° C. After all the HNO₃ has been added, pour the mixture over 50 g. of ice. Filter off the crude product and recrystallize from ethyl alcohol to obtain the following product which melts at 122.5° C. (uncorrected):

Analysis.—Calculated for C₉H₉N₃O₇: C, 39.86; found C, 40.27; H, 3.34; found, C, 3.02; N, 15.5; found, N, 15.2.

IV Preparation of 2,4,6 trinitro-3-isopropylphenol reagent

For analytical work, a sodium salt is prepared of the 2,4,6 trinitro-3-isopropylphenol. To this end, and aque-

ous solution of the above identified isopropylphenol is first rendered basic by the addition of NaOH, and to this is added a concentrated water solution of NaCl which precipitates the sodium salt of 2,4,6 trinitro-3-isopropylphenol as bright yellow crystals which may be filtered off. Qualitative tests may be performed by adding a saturated water solution of the sodium salt to dilute aqueous solutions of chlorides or nitrates of the cations being tested with the following results:

	Cation	Result
10	Na ⁺	Negative.
	Li ⁺	Do.
15	Cu ⁺⁺	Do.
	Ca ⁺⁺	Do.
	Mg ⁺⁺	Do.
	Ni ⁺⁺	Do.
	Al ⁺⁺⁺	Do.
	Hg ⁺⁺	Do.
	Co ⁺⁺	Do.
20	Zn ⁺⁺	Do.
	Mn ⁺⁺	Do.
	Cr ⁺⁺⁺	Do.
	Cd ⁺⁺	Do.
	Fe ⁺⁺	Do.
	Cs ⁺	Do.
	NH ⁺	Do.
25	La ⁺⁺⁺	Positive.
	Pb ⁺⁺	Do.

Ammonia complexes of the following ions give well defined crystalline precipitates:

30	Cu ⁺⁺
	Ni ⁺⁺
	Co ⁺⁺
	Cd ⁺⁺
	Zn ⁺⁺

I claim:

1. A trinitrophenol derivative selected from the group consisting of 3-methyl-5-n-propyltrinitrophenol, 2,4,6-trinitro-isopropylphenol and the sodium salts thereof.
2. A reagent for the qualitative separation of barium, strontium and calcium consisting of the sodium salt of 3-methyl-5-n-propyltrinitrophenol.
3. A reagent for the qualitative separation of lanthanum and lead consisting of the sodium salt of 2,4,6-trinitroisopropylphenol.
4. 2,4,6-trinitro-isopropylphenol.
5. 3-methyl-5-n-propyltrinitrophenol.
6. The method of qualitatively separating barium from barium, strontium and calcium comprising, preparing a reagent in the form of an aqueous solution of the sodium salt of 3-methyl-5-n-propyltrinitrophenol, and adding said reagent to a mixture of barium, strontium, and calcium contained in a solution which contains non-interfering metals to precipitate only barium in large quantities.
7. The method of performing a qualitative analysis for a metal selected from the group consisting of lanthanum and lead comprising, adding a reagent consisting of an aqueous solution of the sodium salt of 2,4,6-trinitro-isopropylphenol to a solution suspected of containing an ion of said metal group, the last-named solution being free of interfering material.
